UNITED STATES PATENT OFFICE.

CLARENCE ELLIS BIRCH, OF LAWRENCE, KANSAS.

WRITING-CHART.

1,216,405.

Specification of Letters Patent. Patented Feb. 20, 1917.

Application filed August 3, 1916. Serial No. 112,963.

To all whom it may concern:

Be it known that I, CLARENCE ELLIS BIRCH, a citizen of the United States, residing at Lawrence, in the county of Douglas and State of Kansas, have invented certain new and useful Improvements in Writing-Charts; and I do declare the following to be a full, clear, and exact description of the invention, such as will enable others skilled in the art to which it appertains to make and use the same.

This invention relates to new and useful improvements in writing charts, and the primary object of the invention is to provide means for holding a plurality of interchangeable and reversible sections having script letters on the opposite sides of the same that may be arranged to form expressions in script for a purpose of teaching penmanship or other studies of letters and words.

Another object of this invention is to provide a writing chart of this character whereby the sections upon which the script letters are, may be easily and quickly interchanged or reversed to form new sentences or words if desired.

A further object of the invention is to provide a writing chart that is provided with compartments behind the section holder to hold additional script sections so that they may be easily located when desired for use.

Another object of the invention is to provide a device of this character which is easily and simply constructed, inexpensive to manufacture and one which will be very efficient in operation.

With these and numerous other objects in view, my invention consists in the novel features of construction, combination and arrangement of parts herein referred to and more particularly pointed out in the specification and claims.

In the accompanying drawings:

Figure 1 is a front elevation of a portion of the chart showing one of the sections positioned therein;

Fig. 2 is a vertical section taken on the line 2—2 of Fig. 1;

Fig. 3 is a top plan view of Fig. 1;

Fig. 4 is a front elevation of the chart showing the sections positioned therein to spell a word;

Figs. 5 and 5^a are partial views of opposite sides of one of the letters;

Figs. 6 and 6^a are partial views of oppo-

site sides of one of the letters that employ a slightly different type of joining; and

Fig. 7 is a vertical section through the holder showing a slightly different arrangement whereby the same is used on opposite sides.

In describing my invention, I shall refer to the drawings in which similar reference characters designate corresponding parts throughout the several views and in which the numeral 1 designates a holder employed in this chart, which comprises a longitudinally extending strip with bent upper and lower edges 2 and 3 that form grooves to receive the interchangeable letter sections therein. The back of the strip 1 is provided with a plurality of compartments 4, each of sufficient width to receive therein a number of additional letters, that may be used when desired. These compartments 4 are slightly shorter than the length of the letters, so that the letters will project therefrom and be readily accessible. If desired, the holder may be also provided with additional grooves 5 on the top and bottom edges of the same as clearly shown in Fig. 7 of the drawings, whereby both sides of the chart may be used.

The letters which form the basis of this invention are placed on a plurality of sections formed with some slightly flexible material, preferably cardboard, and which are formed in the shape of narrow strips designated by the numeral 6 and which have script letters 7 placed on the opposite sides of the same. These sections 6 are not quite as long as the distance between the grooves at the top and bottom edges of the holder, so that when it is desired to place one of the sections in the holder, it is only necessary to insert one end of the same in the upper groove, and to move it upward until it strikes the top of the same whereupon the bottom edge of the section will drop into the bottom groove, and the section will be securely held in the holder. If desired, the section 6 may have printed thereon in one of the upper corners a small letter corresponding to the letter on the face of the same, which is used for identification when a number of these sections are placed in the compartments behind the holder.

The most essential feature of this invention is the formation of the script letters on the sections in such a manner that the letters are adapted to be joined so that it

is possible to exhibit various words or sentences in writing with this chart. The initial and final stroke of all of the letters on the sections terminate at the opposite side edges of the same, and when correctly positioned in the holder, the letters may be so joined that their terminals will connect to form the written word or sentence.

In Figs. 5 and 5^a of the drawings, I have illustrated one of the sections showing both sides of the same, each having a single script letter placed thereon. In Fig. 5 it will be noted that the initial stroke 8 of the letter 7 and the final stroke 9 of the same are disposed in a single transverse line, while in Fig. 5^a which shows the reverse side of this section, the initial stroke 10 is disposed in a transverse line above the transverse line in which the final stroke 11 of the same is positioned.

Certain letters, however, cannot be connected by the letter joining illustrated in Fig. 5 of the drawings, these letters being B, O, V and W, and for them I have shown 25 a slightly different arrangement as clearly illustrated in the section having thereon the letter O and shown in Figs. 6 and 6^a of the drawings. Fig. 6 illustrates one side of the section corresponding to the side of the section shown in Fig. 5 of the drawings, and it will be noted that the initial stroke 12 and final stroke 13 on this section, while disposed in a single transverse line, is positioned in a line higher than the transverse 30 line, in which the initial and final strokes of the other section are placed. The reverse side of the section illustrated in Fig. 6^a is also provided with an initial stroke 14 and a final stroke 15 that are disposed in spaced 35 transverse lines corresponding to a side of the section illustrated in Fig. 5^a of the drawings, but it will be noted that in this letter the initial stroke is disposed in a transverse line below the center of the letter, while the final stroke is disposed in a line above said center, while in the letter shown in Fig. 5^a the initial stroke is in a line above the center, while the final stroke is below the same.

There are three types of letters illustrated 50 in this device, the first of which is shown in Fig. 5, the second in Fig. 5^a, and the third in Fig. 6 of the drawings.

Each of the three types of letters, however, bear one general characteristic inasmuch as they have their terminals on one side of the section disposed in a single transverse line, while on the opposite side they are disposed in spaced transverse lines. In the majority of letters, however, the spaced 55 terminals have the final stroke disposed in a single plane with the terminals of the letter on the opposite side, while the initial stroke of the terminals is spaced above any of the remaining terminals of both sides.

60 65 However, in the letters B, O, V and W,

this positioning is reversed, and the spaced terminals have their final strokes disposed in a single plane with the terminals of the letter on the opposite sides of the section, while the initial stroke is positioned below these 70 terminals.

This positioning of the various letters gives a high and low joining at a uniform distance from the base line of writing and causing the letters to unite when placed side 75 by side. In Fig. 4 of the drawings, I have the letters united to spell the word "joined" and in this figure, I have shown a capital letter at the beginning of the word of a larger script than the other letters, but owing to the fact that this capital letter is not interposed between sections, the formation of the same is not of primary importance. The capital merely follows out the type of script used in the letters, and it may be 80 fixed to the head of the word as clearly shown.

When it is not necessary to use in the word the letters B, O, V or W, all the sections may be joined by use of the low joinings, that is, the side of the sections which is illustrated in Fig. 5 of the drawings. When however, it is necessary to use one of the above mentioned letters, it will be necessary to reverse the card following this letter 90 to the side shown in Fig. 5^a of the drawings, whereupon the initial stroke of the same will connect with the final stroke of said letter, while the final stroke will once more resume its normal low joining. By this connection, 95 any desired word may be exhibited in the script.

In the spelling of certain words there is the additional possibility of using two or more of the letters B, O, V, or W in succession, and when this occurs, their joining is accomplished by the script letter of the type illustrated in Fig. 6 of the drawings. By this type of letter as many of these certain letters may be joined in succession as desired 100 and when it is once more desired to resume the normal letter joining suitable for the other script letters the type of letter illustrated in Fig. 5^a of the drawings is applied 105 as has been hereinbefore described.

The sections 6 may be positioned within the card holder at an angle thereto, or they may be arranged vertically with respect to the same. When the sections are arranged at an angle, a script alphabet of a greater 110 angle may be employed than when vertical sections are used.

The type of holder employed in this chart may be varied when desired, it being essential that some support for the various sections be used that will hold the upper and lower edges of the same in alinement. When the type illustrated in Figs. 1 to 4 of the drawings is used, if desired, the letters may be additionally secured in position by means 115 120 125 130

of small wedges 16 that are driven in between the edge of the lower groove and the lower portion of the section to lock the same in position.

5 From the foregoing description of the construction and operation of my improved writing chart, the manner of applying the same to use and the operation thereof will be readily understood and it will be seen that
10 I have provided a simple and efficient chart of this character for carrying out the objects of the invention.

I claim:

15 1. A writing chart comprising a plurality of interchangeable reversible sections, each section having a script letter on its opposite sides, the initial and final strokes of said letters terminating at the opposite side edges of the sections, the terminals of the letters
20 on one side of each section being disposed in a single transverse line, and the terminals of the letters on the opposite side being disposed in spaced transverse lines whereby the sections may be arranged to exhibit different expressions in script.

25 2. A reversible section for a writing chart having a script letter on each of its opposite sides, the initial and final strokes of said letters terminating at the opposite side edges

of the section, the terminals of the letter on one side of the section disposed in a single transverse line, the terminals of the letter on the opposite side of said section disposed in spaced transverse lines, and one terminal of said last letter positioned on the same transverse plane as the terminals of the opposite letter.

3. A writing chart comprising a plurality of interchangeable reversible sections, each section having a script letter on its opposite sides, the initial and final strokes of said letters terminating at the opposite side edges of the sections, the terminals of the letters on one side of each section being disposed in a single transverse line, the transverse terminal line in certain sections being spaced from the transverse line of the remaining sections on said sides, and the terminals of each letter on the opposite sides of said sections being disposed in spaced transverse lines.

In testimony whereof, I have hereunto set my hand in the presence of two subscribing witnesses.

CLARENCE ELLIS BIRCH.
